UNITED STATES PATENT OFFICE

JESSE T. RHODES, OF BROOKLYN, NEW YORK

DESIGN FOR A CLOCK CASE

Application filed November 25, 1929. Serial No. 33,555. Term of patent 7 years.

To all whom it may concern:

Be it known that I, JESSE T. RHODES, a citizen of the United States, residing at Brooklyn, in the county of Kings and State of New York, have invented a new, original, and ornamental Design for a Clock Case, of which the following is a specification, reference being made to the accompanying drawing, forming part thereof.

Fig. 1 is a front elevation of a clock case, showing my new design; Fig. 2 is a rear elevation; and Fig. 3 is a side elevation of the same.

I claim:

The ornamental design for a clock case as shown.

JESSE T. RHODES.
